2,217,458

STEAM GENERATOR AND WATER HEATER

Edward Frank Spanner, Blackheath, England

Application October 20, 1937, Serial No. 169,993
In Great Britain January 29, 1937

2 Claims. (Cl. 122—7)

This invention relates to improvements in steam generators and water heaters and has particular reference to such devices as are heated by waste hot gases such for example as the exhaust gases from Diesel engines.

The principal object of the present invention is to provide a very simple but efficient device for the generation of steam by means of waste gases.

In the drawings:

10 Fig. 1 is a longitudinal section through a waste heat recovery unit of modified construction receiving waste gases from four independent sources;

15 Fig. 2 is a cross section of the construction shown in Fig. 1 taken on the line 2—2 of that figure;

Fig. 3 is a cross section through a waste heat steam generator utilising gases from three independent sources;

20 Referring to the drawings, 1 denotes an outer shell, and 3 the two tube plates connected to the outer shell 1 at the external peripheries thereof. A nest of water tubes 6 including stay tubes 7 is provided for strengthening the tube plates 3. A tube 51 is arranged axially in the outer shell 1 and connected to the tube plates 3 by their inner peripheries.

25 The water and steam space in this construction is completed by the ends 21 which connect the tube 51 to the outer shell 1, the tube 51 as well as the outer shell 1 being provided with openings for the passage of the heating gases.

30 The arrangement shown in Figs. 1 and 2 is suitable for the utilisation of gases from four independent sources, said gases being admitted to the nests of water tubes 6 by openings 8 in the outer shell and allowed to escape through the openings 91 in the central tube 51.

35 To maintain the longitudinal strength of this structure, reinforcing elements 13 are mounted in the openings 8 and 91 and in order to prevent intermingling of the different streams of waste gas, partitions 181 are arranged between the various sections and the openings 8 are provided with 40 separate inlet connections 162.

45 In some cases it may be desirable to provide for greater distribution of the hot gases during their flow through the nests of water tubes 6 than is possible in the arrangements described and to 50 this end the partitions 181 may be arranged tangentially to the central tube 51 as shown in Fig. 3.

In the construction shown in Fig. 3 gas from

three separate sources is provided for and the openings 8 and 91 are reinforced by members 13 as before, the openings 8 being provided with inlet connections 163.

5 I claim:

1. An improved steam generator and water heater for waste heat recovery comprising an outer tension resisting substantially cylindrical shell, a substantially cylindrical conduit for hot gas extending axially throughout said shell, end 10 covers for said shell through which said conduit passes, two tube plates mounted in said shell in parallel transverse planes disposed about halfway between the transverse middle plane of said shell and its end covers, respectively, said tube plates being peripherally connected to said shell and said conduit to form two spaced annular water and steam chambers, compression resisting water tubes mounted in said tube plates and axially connecting said two water and steam chambers, a 20 hot gas admission port in said shell to admit hot gas to the space between said tube plates in a direction transversely of said water tubes, and a hot gas discharge port in the portion of said cylindrical conduit between said tubes. 25

2. An improved steam generator and water heater for waste heat recovery comprising an outer tension resisting substantially cylindrical shell, a substantially cylindrical conduit for hot gas extending axially throughout said shell, end 30 covers for said shell through which said conduit passes, two tube plates mounted in said shell in parallel transverse planes disposed about halfway between the transverse middle plane of said shell and its end covers, respectively, said tube 35 plates being peripherally connected to said shell and said conduit to form two spaced annular water and steam chambers, partitions extending in the space between said tube plates from the inner periphery of the shell to the outer periphery 40 of the conduit to subdivide said space into a plurality of compartments, a plurality of compression resisting water tubes in each compartment mounted in said tube plates and axially connecting said two water and steam chambers, a 45 hot gas admission port in said shell for each of said compartments to admit the hot gas to the compartment in a direction transversely of said water tubes, and a hot gas discharge port for each compartment connecting the same with the 50 central conduit.

EDWARD F. SPANNER.
